UNITED STATES PATENT OFFICE.

WILLIAM H. VOSS, OF DAVENPORT, IOWA.

WASHING-MACHINE.

1,200,278.

Specification of Letters Patent.

Patented Oct. 3, 1916.

Application filed December 26, 1913. Serial No. 808,765.

To all whom it may concern:

Be it known that I, WILLIAM H. Voss, a citizen of the United States, residing at Davenport, in the county of Scott, State 5 of Iowa, have invented a new and useful Improvement in Washing-Machines, of which the following is a specification.

The present invention relates to washing machines of the platform type wherein the 10 washing machine tub is provided at one end thereof and the wringer being slidably mounted upon the platform so that the clothes may be wrung directly from the washing machine tub to another clothes receiving tub, or from the second tub into a third tub as the case may be, and has for its object to provide a washing and wringing mechanism suitable for driving mechanism adapted for a convenient and economical 15 cleansing and handling of the clothes.

Another object of the invention is to provide a gear connection between the source of motor supply and the washing machine, whereby the washing mechanism within the 20 tub may be operated for a short period in one direction and then operated in its opposite direction to give an alternating action thereto.

A further object of the present invention 25 is to provide a washing machine tub of the horizontal type having a drum so constructed as to prevent the same from tearing or otherwise injuring the clothes deposited therein.

With above and other objects in view the invention consists of the novel features of construction, combination and arrangement of parts as will be hereinafter more fully described and particularly pointed out in 30 the appended claims.

In the drawings: Figure 1 is a side elevation of a washing machine of the platform type, embodying my invention. Fig. 2 is an end elevation of the same, showing the 35 gear casings thereof in section. Fig. 3 is a bottom plan view of the platform, illustrating the washing and wringing gearing as applied thereto. Fig. 4 is a vertical transverse section on the line 4-4 Fig. 1. Fig. 5 is a detail elevation of the trip mechanism as shown in one position. Fig. 6 is a similar view illustrating the trip mechanism 40 when in another position. Fig. 7 is a detailed transverse section through the tub. Fig. 8 is a detail longitudinal section

through the tub. Fig. 9 is a detail view, and Fig. 10 is a detail sectional view of the trip mechanism.

Reference now being had to the accompanying drawings wherein like and corresponding parts are designated by similar reference characters throughout the several views, the letter P indicates a platform having mounted upon one end thereof washing machine tub W and slidably mounted 60 upon the opposite end of the platform a wringer R.

Journaled within bearings 1 supported upon platform P is a driving shaft 2 carrying a belt pulley 3 connected to a suitable motor for driving the mechanism as will hereinafter be more fully described. Also carried by the platform are bearings 4, having journaled therein a squared shaft 5 and extending in alinement with the squared 65 shaft 5 is the washer driving shaft 6, being supported at one end within the bearing 7 carried by the platform and its opposite end being adapted to be connected to the squared shaft 5 through the clutch 8. Pivotedly 70 connected to the bracket 9, carried by the platform is an operating lever 10 in the available use of the operator whereby the clutch 8 may be thrown into and out of 75 engagement with the squared shaft 5 for a purpose which will be later described. Keyed to the power shaft 2 is a sprocket 80 wheel 11 which is connected by means of a sprocket chain 12 to a large gear 13, keyed upon and carried by the squared shaft 5. 85 From this it is obvious that upon the rotation of the shaft 2 a continuous rotation will be transmitted to the squared shaft 5 90 through the sprocket and chain gearing as described.

Slidably mounted on the rails 14 and 15 is a wringer supporting frame 16, having mounted thereupon the wringer R. The wringer is of the usual construction and has extending from one roller shaft thereof the shaft 17 carrying a gear which is permanently in mesh with a bevel gear carried by the vertical shaft 18 and the mentioned gears are inclosed within a casing 19. The lower end of the vertical shaft 18 carries a bevel pinion 20 which continually meshes with a pair of pinions freely mounted upon the horizontal drive shaft 21. The drive shaft 21 is provided with a bevel gear 22, being in mesh with a bevel gear 24 carried by the 95 100 105 110

square shaft 5 but slidably mounted thereupon. A sleeve 25 is also slidably mounted upon the squared shaft 5 and has extending therefrom a bracket 26 which forms a bearing 5 for the drive shaft 21. The pair of beveled gears which are in continuous mesh with the bevel gears 20 are adapted to be simultaneously shifted upon the movement of the casing 27 for throwing the said bevel gears 10 into engagement with the clutch 28 carried by the drive shaft 21, whereby the wringer rolls may be operated in either direction as the case may require. To provide means for shifting the casing 27 a short lever 29 is provided, having its upper end connected to the casing through the ball and socket connection as shown and its opposite end of the lever being connected to a foot treadle lever 30. From this it is obvious that 15 the casing 27 may be shifted by the foot treadle, but to provide means for shifting the same by hand a control rod 31 is provided which is connected to the foot treadle through the bell crank 32.

25 Carried by the platform are vertically extending angle arm supports 33 being connected adjacent their upper ends by means of the angle bar 34 and carried by these angle bars are cross pieces 35 and 36 respectively. The washing machine tub 37 is 30 made of sheet metal and is suspended from the cross pieces 35 and 36 respectively and lower end of the tub has a contour substantially the same as the outer configuration 35 of the clothes receiving drum 38. To prevent the water from splashing from the tub during the operation of the machine a cover 39 is pivotally mounted upon the tub and may be easily and readily swung out of the 40 way whereby the operator may easily gain access within the tub.

The clothes receiving drum which is supported within the tub comprises side members 40 being connected by cross pieces 41 45 which are spaced at intervals and are made of wood. Counter sunk within the sides of the cross pieces 41 are perforated metal strips 42 which permit the water within the tub to enter the drum containing the 50 clothes to be washed. The inner faces of the wooden strips 41 are corrugated as is shown and by counter sinking the perforated metal plates 42 within the sides of the wooden strips the clothes will be prevented 55 from coming in contact with the edges of the metal plates which would tend to tear or otherwise injure the clothes. The metal strips also add to the strength of the drum as they keep the wooden cross pieces from 60 bulging or warping and thereby insure durability to the structure. The drum is of a circular contour and has provided within the wall thereof a door 43 whereby the operator may gain access to the interior of 65 the clothes receiving drum.

To provide means for supporting the drum within the tub the outer faces of the side members 40 have secured thereto metal disks 44 and 45 respectively. The disk 45 has extending therefrom a stub shaft 46 having its 70 outer end of reduced diameter which is adapted to rest within the bearing 47 supported upon the inner face at one side of the tub. The bearing 47 is provided with a restricted portion 48 at its lower end in which the 75 stub shaft normally rests but when removing the drum from the tub as will be later described, the stub shaft will be raised so that it will rest within the enlarged portion 49 of the bearing as more clearly disclosed in 80 Fig. 9 of the drawings. The opposite disk 44 carried by the drum has formed therewith an extension 50 having recesses formed in the outer face thereof for the reception of the lugs 51 carried by the driving disk 85 52. In removing the drum from the tub the stub shaft 46 is raised until it is permitted to rest within the enlarged portion 49 of the bearing 47 whereby the drum may be shifted laterally to disengage the enlarged 90 portion 50 from the lugs 51 and then the opposite side of the drum is raised to the same level. The drum is then shifted in the opposite direction, releasing the stub shaft from the bearing 47 whereby it may be 95 readily removed from the tub in case of cleansing the interior of the tub or drum.

To provide means for rotating the drum alternately in opposite directions, I provide a shaft 53 being journaled within bearings 100 100 formed integrally with the gear casings 54 and 55 respectively. The lower end of the shaft 53 is provided with a bevel gear 56 which is in mesh with a bevel gear 57 carried by the outer end of the shaft 6. The 105 gears 56 and 57 respectively are housed within the casing 55. The upper end of the shaft 53 has loosely mounted thereon a pair of beveled gears 58, which are in constant mesh with the bevel gear 59 carried by shaft 110 60 which is journaled within a bearing formed integrally with the casing 54. The shaft 60 carries at its inner end the disk 52. The gear casing 54 is supported upon the outer face of the tub and has projected 115 therefrom a semicircular flange 61 which extends within the tub and forms a support for the member 50 when removing the drum from the tub. For connecting the gears 58 alternately to the shaft 53 so that the shaft 120 60 may be rotated in opposite directions at predetermined intervals, a clutch 62 is keyed to the shaft 63 and slidably mounted thereupon for engaging the clutch members carried by the bevel gears 58. A lever 63 125 is pivotally mounted as at 64 upon the gear casing 54 and is provided with a yoke 65 for engagement with the clutch whereby the latter may be shifted for reversing the direction of the shaft 60.

To provide means for automatically shifting the clutch 65 at predetermined intervals I provide a trip mechanism which will be herein described. Loosely mounted upon the shaft 2 is a sprocket wheel 66 being connected to a sprocket wheel 67 fixed to the shaft 6 by means of the sprocket chain 68. Whereas I have shown the sprocket wheel 66 freely mounted upon the shaft 2 it is to be understood that this shaft 2 does not transmit any motion to the sprocket wheel 66 but merely provides a support therefor. Depending from the platform is a bracket 69 having a cam lever pivotally connected thereto as at 70. Carried by the chain 68 is a roll 71 which is adapted to ride upon the lower face of the cam lever for operating the lever during the traveling movement of the roller 71. A stub shaft 72 is journaled within the frame and has keyed thereto a ratchet 73 at one side of the platform frame and a cam 74 at the opposite side of the platform frame. A crank sleeve 75 is pivotally mounted upon the stub shaft carrying a pawl 76 for engagement with the ratchet wheel and an arm being connected to the cam lever by means of the pitman link 77. When the roller 71 through its traveling motion contacts the end 78 of the cam lever the crank will be operated for moving the pawl 76 back into engagement with the next tooth carried by the ratchet 73 as shown in Fig. 5 of the drawings but when the roller 71 has engaged the free end 79 of the cam lever it will force the free end upwardly thereby turning the ratchet which in turn carries with it the cam 74 through the stub shaft 72. Pivotally connected at one end of the lever 63 is a link 80 provided at its lower end with an elongated slot 81 through which extends the shaft 72. Projecting from the outer face of the link 80 are rollers 82. From this it will be seen that upon the rotation of the shaft 72 through the trip mechanism as described the cam 74 will engage the rollers 82 and shift the link 80 in opposite directions, whereby the clutch 65 will be thrown into and out of engagement with the bevel gears 58 whereby the clothes receiving drum will be operated alternately in opposite directions.

Whereas I have only shown one of the rollers 71 upon the sprocket chain 60 it is of course understood that any number of these rollers may be provided as will be necessary in determining the number of times the cam 74 should be rotated for operating a clutch whereby the drum will be rotated in opposite directions.

From the particular configuration of the cam 74 it will be noted that the clutch 55 will be held out of engagement with the gears 58 a short time when changing from one to the other. When the clutch is held in this neutral position the clothes receiving

drum will be permitted to turn by the momentum gained during its driving rotation and before reversing its direction of rotation the drum will come to a stop, or almost to a stop, thereby no excess load will be thrown on the gearing in reversing the direction of rotation of the clothes receiving drum.

Various details of the mechanism herein disclosed may be changed and modifications may be made without departing from the spirit of the invention or sacrificing the efficiency of the same.

I claim:

1. In apparatus of the class described, a frame, a rotary drum in said frame, a gear rigid with the drum, a shaft, beveled gears on said shaft in mesh with said first named gear, a clutch member interposed between said bevel gears to operatively connect either thereof with the shaft, a lever for throwing said clutch, a chain having a projection thereon for operating said lever.

2. In apparatus of the class described, a frame, a rotary drum in said frame, a gear rigid with said drum, a shaft having a pinion thereon in mesh with said gear for oscillating said drum, a clutch member for determining the direction of movement of said drum, means including an intermittently advanced chain for operating said clutch member, substantially as described.

3. In apparatus of the class described, a frame, a rotary drum in said frame, a gear on said drum, a shaft, beveled gears on said shaft in mesh with said first named gear, a clutch member for alternately clutching said bevel gears to said shaft, a bent lever for operating said clutch, an intermittently operated chain having a projection thereon for engagement with said bent lever for shifting said clutch.

4. In apparatus of the class described, a frame, a rotary drum therein, a gear on said drum, a reversible drive, comprising a pair of beveled gears in engagement with said first named gear, a clutch member for operatively connecting either of said bevel gears with said gear, a link for operating said clutch member, a cam for operating said link and means for shifting said cam into operative position, comprising a bent lever, a chain having a projection thereon for engagement with said bent lever whereby said cam will be gradually moved into operative position permitting a slow shifting of said clutch for in turn permitting the momentum of the drum to be dissipated prior to its reversal.

5. In apparatus of the class described, a frame, a rotary drum therein, connections for operatively positively driving said drum, comprising a reversible drive including a clutch, a cam for shifting said clutch, a ratchet on said cam, a pawl for moving the

ratchet, a link for operating said pawl, a bent lever having two extended portions one on either side of its pivot, a chain having a projection thereon for successively engaging said extending portions of said bent lever for causing said lever to operate said pawl.

5 In witness whereof, I hereunto sub-

scribe my name to this specification in the presence of two witnesses.

WILLIAM H. VOSS.
